UNITED STATES PATENT OFFICE.

THOMAS CARLTON ALBIN, OF MANISTIQUE, MICHIGAN.

PROCESS AND MEANS OF COOLING KILNS.

Application filed February 15, 1923. Serial No. 619,226.

To all whom it may concern:

Be it known that I, THOMAS CARLTON ALBIN, a citizen of the United States, and a resident of Manistique, in the county of Schoolcraft and State of Michigan, have invented a new and useful Improvement in Processes and Means of Cooling Kilns, of which the following is a full, clear, and exact description.

10 My invention relates to improvements in the process of cooling kilns, more particularly for cooling charcoal kilns, and the apparatus for carrying out the process, and it consists in the steps, combinations, constructions, and arrangement of parts herein described and claimed.

In the operation of charcoal kilns, considerable of the expense involved is due to the fact that so much time is taken in 20 the cooling of the kiln and its contents to a point where it may be safely opened without the charcoal igniting when the air strikes it. Thus in certain types of kilns which are in common use, it takes from 25 twelve to eighteen days for the kiln to cool.

An object of the present invention is to provide a process in which the time taken in cooling the kiln is greatly reduced, thereby increasing the capacity of the kiln and 30 lowering the cost of production.

A further object of my invention is to provide a process of rapidly cooling kilns in which such cooling may be effected without any injury to the resulting product.

35 A further object of my invention is to provide a means for quickly cooling kilns which may be used in connection with the ordinary charcoal kiln without necessitating any change in the body of the kiln proper.

A further object of my invention is to provide a cooling means which is comparatively simple in construction and relatively inexpensive to install.

45 Other objects and advantages will appear in the following specification, and the novel features of the invention will be particularly pointed out in the appended claims.

My invention is illustrated in the accompanying drawings, forming part of this application, in which

Figure 1 is a sectional view of a kiln equipped with my improved cooling mechanism, and

50 Figure 2 is a top plan view of an em-

bodiment of the mechanism illustrated in Figure 1.

In the drawings, 1 denotes the floor of an ordinary kiln, and 2 the side walls. The latter are provided with the usual drawing door 3. The top of the kiln, which is shown at 4, has a filling door 5 and a scuttle hole 6. A chimney 7 communicates with the interior of the kiln at 8. The construction thus far described is ordinary. The 60 walls of the kiln may be made of any suitable material and the kiln may be of any desired dimensions.

My improved process and means for the cooling of kilns may be carried out by 70 means of a convoluted pipe 9 which consists in a plurality of short pipes connected in series with one another by means of return elbows 10. One end of the pipe 9 has connected thereto an elbow 11 to which a 75 coupling 12 is attached. This coupling 12 is arranged to engage with the scuttle hole 6 to occasion an air-tight connection therewith.

A rotary suction fan 13 is provided and 80 the intake port thereof is connected by means of a pipe 14 to the opposite end of the pipe 9. The outlet port of the suction fan 13 has connected thereto a short downwardly bent pipe 15 having a coupling 85 member 16 at the lower end thereof, which coupling 16 is arranged to engage with the chimney 7 to form an air-tight connection therewith. It should be noted at this time that the coupling members 12 and 16 may 90 be engaged or disengaged with the scuttle hole 6 and the chimney 7 respectively at will, and therefore the entire mechanism comprising namely, the pipe 9 and the suction fan 13, may be lifted out of engagement with the kiln and moved by any suitable mechanism (not shown) to another kiln. This is a great advantage since in the 95 ordinary charcoal manufacture there are a great many kilns in the same room, and if the cooling mechanism could not be moved from one kiln to another, it would be necessary to employ a separate mechanism for each kiln, which would greatly increase the expense of the plant.

The chimney 7 has connected thereto a smoke main 17 by means of the short connecting tube 18. The connection between the smoke main 17 and the chimney 7 is 100 of course air-tight. The primary purpose 110

of the smoke main is to carry away the smoke from the kiln when the contents thereof have been ignited.

It is well known that occasionally when the contents of the kiln begin to cool the pressure therein is diminished and consequently air from the outside is introduced to the kiln if the kiln is not air-tight at any place. Since it is not uncommon that a kiln shall be possessed of slight crevices or leaks between the filling door and the walls, or the drawing door and the walls, some efficient means is necessary to introduce an inert gas to the kiln under pressure so as to prevent the air on the outside of the kiln from entering the kiln and causing harmful combustion of the contents thereof.

Such means I have provided in my present invention in a pipe 19 which is connected at one end to the smoke main 17 and at its opposite end to the pipe 14 adjacent the intake port of the suction fan 13, as shown at 20. A damper 21 is disposed in the pipe 14 intermediate the point 20 where the pipe 19 connects with the pipe 14, and one end of the convoluted cooling pipe 9.

There is also a damper 22 disposed in the pipe 19 intermediate its length, as shown in Figure 2.

From the foregoing description of the invention, the operation thereof may be readily understood. In preparing the kiln, the wood is introduced in precisely the same manner as if my improved process and means of cooling the kiln were not to be employed. The scuttle hole 6 is sealed and the fire is started. At this time the cooling mechanism is not connected to the kiln, but may be entirely removed therefrom. After the fire has burnt out, the process of cooling the kiln must begin. In the ordinary kiln, it is necessary to wait from twelve to eighteen days before the contents of the kiln may cool sufficiently to permit the opening of the kiln without combustion of the contents thereof.

My present invention is for the purpose of shortening the cooling time, and thereby greatly decreasing the cost of producing charcoal. To this end I remove the seal from the scuttle hole 6 and secure the coupling 12 thereto. I then connect the coupling 16 to the chimney 7, as shown in Figure 1, and operate the suction fan 13. The result is that gaseous contents of the kiln will be drawn up through the relatively long pipe 9 by way of the scuttle hole 6, through the suction fan 13 and into the chimney 7 by way of the coupling 16. Thus the hot gaseous contents of the kiln will be kept in constant circulation through the convoluted pipe 9 which may radiate heat from the hot gaseous contents of the kiln as it passes therethrough, and thereby gradually lower the temperature of the gases in the kiln until it is safe to open the kiln and

remove the contents without danger of combustion of the contents when the outside air which contains oxygen comes into contact therewith.

Let us assume that the kiln is not altogether air-tight and that as the contents thereof cool down, pressure of the air on the outside of the kiln becomes greater than the pressure of the air on the inside. Under ordinary circumstances, the result would be that a certain amount of the atmosphere from the outside of the kiln would enter the kiln and cause undue and harmful combustion of the contents thereof.

To prevent this undue and harmful combustion of the contents of the kiln by virtue of the entrance of air from the outside, I connect the pipe 14 with the smoke main 17 at a point immediately in front of the suction fan. This is done by opening the damper 22 which completes the connection heretofore described. I then operate the suction fan 13 to cause inert gases and smoke from the smoke main 17 to enter the kiln under pressure and thereby raise the pressure of the gaseous contents of the kiln to greater degree than the pressure of the air outside.

The result would be that no air from the exterior of the kiln may enter, and therefore there will be no harmful combustion of the contents. If the damper 21 is closed entirely, the circulation of the contents of the kiln will cease, but if it is open slightly, the circulation may continue and at the same time the pressure on the interior of the kiln may be maintained at a higher degree than the pressure of the atmosphere on the outside of the kiln.

It should be understood that the embodiment of my invention, the particular structure of which is described in the foregoing specification, is purely illustrative, and that obviously I may employ numerous other forms of apparatus to accomplish the same useful result.

I claim:

1. The herein described means for cooling a charcoal kiln having a scuttle hole and a chimney, which comprises a cooling pipe arranged to be connected at one end with the scuttle hole of the kiln, a suction fan having its intake port connected with the opposite end of said intake pipe, and its outlet port arranged to be connected with the chimney of said kiln.

2. The herein described means for cooling a charcoal kiln having a scuttle hole and a chimney, which consists in a relatively long convoluted cooling pipe, one end of which is adapted to be connected with the scuttle hole of said kiln, a suction fan connected with its intake port to the opposite end of said cooling pipe, means for connecting the outlet port of said suction fan with the chimney of said kiln, and a damper dis-

posed in the cooling pipe adjacent the intake port of said suction fan.

3. The herein described means for cooling a charcoal kiln having a scuttle hole and chimney and a smoke main, which comprises a cooling pipe arranged to be connected at one end with the scuttle hole of the kiln, a suction fan having its intake port connected with the opposite end of said cooling 10 pipe and its outlet port arranged to be connected with the chimney of said kiln, and a smoke conducting pipe connected at one end with said smoke main and at the opposite end with said cooling pipe intermediate the damper of said cooling pipe and the intake port of said suction fan.

4. The herein described process of cooling a charcoal kiln which consists in sealing the kiln all but the scuttle hole and the chimney outlet, in drawing the hot gases from the kiln by way of the scuttle hole, and through a cooling medium where the gases are cooled and in subsequently returning the gases from the cooling medium into the 25 kiln by way of the chimney opening.

5. The herein described steps in a process for cooling a charcoal kiln which consists in sealing the kiln all but the scuttle hole and the chimney outlet, in drawing the hot 30 gases from the kiln by way of the scuttle hole, through a cooling medium where the gases are cooled, in subsequently returning the gases from the cooling medium into the

kiln by way of the chimney opening, and in injecting an inert gas under pressure 35 into the kiln, whereby the internal pressure of the kiln may be maintained at a higher degree than the atmospheric pressure on the exterior of the kiln.

6. The herein described means for cooling a charcoal kiln having a scuttle hole which consists in a relatively long cooling pipe placed exteriorly of said kiln, one end of which is adapted to be connected to the scuttle hole of said kiln, a suction fan connected with its intake port to the opposite end of said cooling pipe, means for connecting the outlet port of said suction fan with the interior of said kiln, and a damper disposed in the cooling pipe adjacent the intake port of said suction fan.

7. The herein described means for cooling a charcoal kiln having a scuttle hole and a smoke main which comprises a cooling pipe disposed exteriorly of said kiln and 55 arranged to be connected at one end with the scuttle hole of the kiln, a suction fan having its intake port connected with the opposite end of said cooling pipe, and its outlet port connected to the interior of said 60 kiln, and a smoke conducting pipe connected at one end with said smoke main and at the opposite end with said cooling pipe adjacent the intake port of said suction fan.

THOMAS CARLTON ALBIN.
